UNITED STATES PATENT OFFICE.

CHARLES MARTIN MALLORY, OF CHATTANOOGA, TENNESSEE.

SHARPENING DEVICE.

No. 801,585.

Specification of Letters Patent.

Patented Oct. 10, 1905.

Application filed February 6, 1905. Serial No. 244,503.

To all whom it may concern:

Be it known that I, CHARLES MARTIN MALLORY, a citizen of the United States, residing at Chattanooga, in the county of Hamilton and State of Tennessee, have invented a new and useful Sharpening Device, of which the following is a specification.

This invention relates to sharpening devices for edge-tools, and has for its object to embody the same in the nature of a hone and to provide certain new and useful improvements whereby the life of the active surface of the hone is materially prolonged and the handling of the device is facilitated.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a perspective view of a hone embodying the features of the present invention. Fig. 2 is a cross-sectional view thereof. Fig. 3 is a longitudinal sectional view on the line 3-3 of Fig. 2. Fig. 4 is a detail view of one of the end plates of the hone.

Like characters of reference designate corresponding parts in each and every figure of the drawings.

In carrying out the present invention there is provided a body or base 1, preferably in the nature of an oblong block of wood to render the same both light, durable, and inexpensive. The upper surface of this body is flat throughout its entire length and width, and the opposite longitudinal edges thereof are provided with corresponding longitudinal grooves or channels 2, extending entirely throughout the length of the body. The edge portions of the body between the grooves or channels and the top are rounded or beveled, as clearly indicated in Fig. 2.

The active surface of the present hone consists of a single piece of relatively soft sheet metal 3, which is fitted flat upon the top of the base or body and is pressed around the edges of the body and into the grooves or channels 2 with sufficient force to retain the plate upon the base without other fastening means.

While it is not absolutely essential to the present invention, it is proposed to guard against endwise play of the metal part 3 by means of metal end plates 4 and 5, which are substantial duplicates in form and are shaped to fit the respective ends of the base, to which they are secured by means of suitable fastenings 6. The opposite upright edges of each plate are cleft to produce corresponding flaps 65 or tongues 7, which are bent into the ends of the grooves or channels 2 and around the end portions of the metal sheet 3, which are forced into said grooves, thereby to prevent endwise looseness of said metal sheet. The upper edges of the end plates 5 should lie within the external surface of the metal part 3, so as to avoid projections in the path of an edge-tool being worked back and forth across the hone. 75

It will here be explained that the outer surface of the metal part 3 is smooth and polished, and it is proposed to apply a granular abrasive material to the metal part when it is desired to sharpen a tool. In order that such abrasive material may always be at hand, there is provided a receptacle 8 to contain granular emery, carborundum, or other suitable material, said receptacle being provided with a perforate shaker-head 9 to facilitate the distribution of 85 the granular material upon the plate 3. This receptacle is carried within a seat or socket 10, formed longitudinally in the body 1 and opening through one end thereof, one of the end plates (shown in the drawings as plate 5) being provided with an opening 11 to give access to the socket 10. A suitable pivotal closure 12 is mounted upon the plate 5, as indicated at 13, and is capable of swinging across the opening 11 to close the same, there being 90 a lip 14 cleft from the plate and sprung outwardly therefrom to form a keeper between which and the plate the free end of the closure 12 is designed to fit, so as to hold the closure in its closed position. The closure is 95 provided with a longitudinally-pressed-out rib portion 15, which stiffens the closure and constitutes a finger-piece for convenience in swinging the closure open.

In using the hone the closure 12 is open, the receptacle 8 is removed, and a suitable quantity of granular abrasive material is shaken upon the metallic surface 3, after which the edge tool to be sharpened is worked back and forth across the metallic surface of the hone 110 in the usual manner.

From the foregoing description it will be

understood that the device of the present invention is exceedingly simple, inexpensive, and durable and is embodied in such form so as to enable the convenient handling thereof.

5 The metallic face 3 is secured to the base member in a simple and effective manner, and the receptacle for containing the abrasive material is removably carried within the base, and therefore always conveniently at hand for immediate use.

Having fully described the invention, what is claimed is—

1. A sharpening device for edge-tools comprising a base having opposite longitudinal edge grooves, a metallic plate fitted snugly to the top of the base and pressed snugly around the edges thereof into the grooves, and plates secured to the ends of the base and provided with tongues bent into the ends of the grooves 15 of the base and across the metal plate to prevent endwise looseness thereof.

2. A sharpening device for edge-tools comprising a base having opposite longitudinal edge grooves and a longitudinal socket intersecting one end, a metallic plate fitted snugly across the top of the base and pressed snugly around the edges thereof into the grooves, metallic end plates secured to the ends of the base and provided with tongues bent into the ends of the grooves and across the metal 25 plate, one of the end plates having an opening registered with the open end of the socket, and a closure for the socket carried by the said end plate.

In testimony that I claim the foregoing as 35 my own I have hereto affixed my signature in the presence of two witnesses.

CHARLES MARTIN MALLORY.
